His Attorney

UNITED STATES PATENT OFFICE.

ROBERT M. GILSON, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed February 17, 1926. Serial No. 88,799.

My invention relates to railway traffic controlling apparatus, and particularly to apparatus of the type comprising a plurality of sections of railway track separated by 5 insulated joints and each provided with governing means controlled by current supplied to the rails of the section.

One object of my invention is to prevent 10 improper operation of the governing means for a section by stray current from an adjacent track section.

I will describe one form of railway traffic controlling apparatus embodying my invention, and will then point out the novel 15 features thereof in claims.

The accompanying drawing is a diagrammatic view illustrating one form of railway traffic controlling apparatus embodying my invention.

20 Referring to the drawing, the reference characters 1 and 1^a designate the track rails of a stretch of railway track over which traffic normally moves in the direction indicated by the arrow. These track rails are 25 divided into a plurality of successive track sections A—B, B—C, etc., by short intermediate portions of track each designated by the reference character D with an exponent corresponding to the location and 30 separated from the adjoining track sections by insulated joints in the track rails. For example, the short intermediate portion D^b dividing section A—B from section B—C, is isolated from the rest of the track by 35 means of two insulated joints 2^b and 3^b in rail 1 and two similar insulated joints 4^b and 5^b in rail 1^a. The two rails of each intermediate portion D are connected together by a jumper 15.

40 Each track section is provided with a suitable source of alternating track circuit current here shown as a track transformer designated by the reference character T and having a secondary 8 connected across the rails adjacent the exit end of the associated section in series with an impedance 7. The primary 9 of each track transformer T is constantly supplied with alternating current from

secondary 10 of an associated line transformer designated by the reference character 50 L with an appropriate distinguishing exponent. Alternating current is constantly supplied to primary 11 of each line transformer L from a suitable source of energy such as an alternator W over line wires 55 14 and 14^a.

Each track section is also provided with a track relay designated in general by the reference character R with a suitable exponent and comprising two windings 12 and 60 13, one of which, 12, is connected across the rails adjacent the entrance end of the section.

Associated with each track relay R is a detector relay designated by the reference 65 character G with an exponent corresponding to the location. Each of these detector relays is designed to be operated by uni-directional current and if supplied with alternating current requires an electromotive force 70 across its terminals of many times the electromotive force required to operate the relay on uni-directional current. In apparatus embodying my invention, the detector relay is never supplied with alternating current 75 of sufficient electromotive force to operate the relay, and for purposes of the present disclosure it is therefore correct to state that the detector relays are responsive to uni-directional current but not to alternating 80 current. Each detector relay G controls the supply of alternating current to winding 13 of the adjacent track relay as will be described hereinafter.

Connected in parallel with each insulated 85 joint 2 is an asymmetrical unit designated by the reference character 6 with a distinguishing exponent which unit is arranged to supply uni-directional current to the adjacent detector relay. Each asymmetrical 90 unit 6 may be of any suitable type such for example as the rectifier disclosed in an application for Letters Patent of the United States, Serial No. 1111, filed January 7, 1925, by Lars O. Grondahl, for uni-directional current carrying devices. 95

Referring particularly to detector relay G^B , this relay is provided with a circuit which may be traced from secondary 8 of track transformer T^B , through wires 16 and 17, winding of relay G^B , wire 18, rail 1^a of intermediate portion D^B , jumper 15, rail 1 of intermediate portion D^B , asymmetrical unit 6^B, rail 1 of section A—B and wire 19 back to secondary 8 of transformer T^B . Under normal conditions, therefore, unidirectional current is supplied to relay G^B from transformer T^B , through the asymmetrical unit 6^B. The circuit for each of the remaining detector relays G is similar to that just traced for relay G^B .

When relay G^B is closed, current flows from secondary 10 of transformer L^B , through wires 21, 22 and 23, front contact 24 of relay G^B , wire 25, winding 13 of relay R^B , wires 26, 27 and 28, back to secondary 10 of transformer L^B . When this circuit is closed, alternating current is therefore supplied to winding 13 of relay R^B , and if, under these conditions alternating current is also supplied to winding 12 of relay R^B , as when section B—C is unoccupied, relay R^B will be energized. The winding 13 of each of the remaining relays R is provided with a circuit similar to that just traced for winding 13 of relay R^B .

The track relays R may be used to control traffic governing means in any suitable manner. In the form here shown each track section is provided with a trackway signal designated by the reference character S with an appropriate exponent and each capable of indicating "proceed" or "stop." When relay R^B is energized, current flows from secondary 10 of transformer L^B , through wires 21, 22 and 29, front contact 30 of relay R^B , wire 31, operating mechanism of signal S^B , and wires 32, 27 and 28, back to secondary 10 of transformer L^B . When this circuit is closed signal S^B indicates proceed. When relay R^B is de-energized, however, signal S^B indicates stop.

As shown in the drawing, section A—B and the section to the right of point C are unoccupied, and a train, indicated diagrammatically at V, occupies section B—C. Detector relays G are all energized and alternating current is therefore supplied to winding 13 of each track relay R . Current is also supplied to windings 12 of relays R^A and R^C , so that these relays are energized and signals S^A and S^C indicate proceed. Winding 12 of relay R^B is shunted by the wheels and axles of train V so that relay R^B is de-energized and signal S^B indicates stop.

Under some conditions it may happen that one or more of the insulated joints 2, 3, 4 or 5 breaks down. In this event the track relay for one section may become improperly energized by stray current from an ad-

jacent track section, even when the former section is occupied by a train. For example, I will assume that insulated joints 2^B and 3^B both break down. Current may then flow from secondary 8 of transformer T^B , through wire 19, rail 1 of section A—B, insulated joint 2^B, rail 1 of intermediate portion D^B , insulated joint 3^B, and rail 1 of section B—C to winding 12 of relay R^B , and thence from rail 1^a of section B—C, through the ground to rail 1^a of section A—B and back to secondary 8 of transformer T^B . The stray current thus supplied to winding 12 of relay R^B might be of sufficient magnitude to energize the relay.

With apparatus embodying my invention, however, a track relay can never become energized by stray current due to a broken down insulated joint. If insulated joint 2^B breaks down asymmetrical unit 6^B will be shunted and relay G^B will be supplied with alternating current from transformer T^B instead of with unidirectional current. But the magnitude of the alternating electromotive force then applied to relay G^B will not be sufficient to operate the relay which will therefore become de-energized. The opening of front contact 24 of relay G^B will interrupt the circuit for winding 13 of relay R^B and will therefore prevent energization of the latter relay, even though current is being supplied to winding 12 of the relay. Similarly, it should be noted that if insulated joint 3^B should break down, the right-hand terminal of relay G^B would be connected with rail 1 of section B—C. As a result of this connection, alternating current would flow from secondary 8 of transformer T^B , through wire 19, rail 1 of section A—B, thence through the ground to rail 1 of section B—C, through the broken down insulated joint 3^B, rail 1 of intermediate portion D^B , jumper 15, rail 1^a of intermediate portion D^B , wire 18, winding of relay G^B , and wire 17 back to secondary 8 of transformer T^B . The alternating current thus supplied to relay G^B would cause the relay to be de-energized and the opening of front contact 24 would de-energize winding 13 of relay R^B .

Similarly, should insulated joint 5^B break down, alternating current would flow from secondary 8 of transformer T^B , through wire 19 to rail 1 of section A—B, thence through the ground to rail 1^a of section B—C, broken down joint 5^B, rail 1^a of intermediate portion D^B , wire 18, winding of relay G^B , and wire 17 back to secondary 8 of transformer T^B . Alternating current supplied to relay G^B over this leakage path would de-energize the relay as explained hereinbefore.

Furthermore, should insulated joint 4^B break down, relay G^B would be connected directly across the impedance 7. The alter- 130

inating potential drop in this impedance would then send an alternating current through the winding of relay G^B and would cause the relay to open.

5. It will be observed from the foregoing that under no condition would a dangerous condition arise, due to a broken down insulated joint.

If the leakage path through the ground 10 which shunts asymmetrical unit 6 is of such high resistance that the relay G is not de-energized, an unsafe condition cannot result because the leakage path will then also have too high a resistance to permit current of sufficient magnitude to leak from one section to the other to energize the track relay.

It should also be pointed out that the 20 circuit for detector relay G is completely checked, for should any fault occur in this circuit, the consequent de-energization of the detector relay would de-energize the adjacent track relay.

Although I have herein shown and de- 25 scribed only one form of railway traffic controlling apparatus embodying my invention, it is understood that various changes and modifications may be made therein within the scope of the appended claims without departing from the spirit and scope of my invention.

Having thus described my invention, what I claim is:

1. In combination, a stretch of railway 35 track divided into two track sections by a short intermediate portion of track separated from both said sections by insulated joints in the track rails, a source of alternating current connected with the rails of one said section, a track relay having two 40 windings one of which is connected with the rails of the other section, and means normally effective but rendered ineffective if any of said insulated joints break down for supplying alternating current to the remaining winding of said track relay.

2. In combination, a stretch of railway 50 track divided into two track sections by a short intermediate portion of track separated from both said sections by insulated joints in the track rails, a source of alternating current connected with the rails of one said section, a track relay having two windings one of which is connected with the rails of the other section, a detector relay, means normally effective but rendered ineffective if any of said insulated joints break down for energizing said detector relay, and means controlled by said detector 55 relay for supplying alternating current to the remaining winding of said track relay.

3. In combination, a stretch of railway 60 track divided into two track sections by a short intermediate portion of track separated from both said sections by insulated

joints in the track rails, a source of alternating current connected with the rails of one said section, a track relay having two windings one of which is connected with the rails of the other section, a detector relay, means normally effective but rendered ineffective if any of said insulated joints break down for energizing said detector relay, and a circuit for the remaining winding of said track relay including a source of alternating current and a front contact on said detector relay.

4. In combination, a stretch of railway 70 track divided into two track sections by a short intermediate portion of track separated from both said sections by insulated joints in the track rails, a source of alternating current connected with the rails of one said section, a track relay having two windings one of which is connected with the rails of the other section, an asymmetrical unit connected across one of said insulated joints, a detector relay responsive to unidirectional current but not to alternating current, a circuit for said detector relay including a source of alternating current and said asymmetrical unit, and means controlled by said relay for supplying alternating current to the remaining winding of said track relay.

5. In combination, a stretch of railway 80 track divided into a first and a second track section by a short intermediate portion of track separated from both said sections by insulated joints in the track rails, a source of alternating current connected across the rails of said first section, a track relay having two windings one of which is connected across the rails of said second section, an asymmetrical unit connecting one rail of said intermediate portion with one rail of said first section, a jumper for connecting together the rails of said intermediate portion of track, a detector relay having one terminal connected with a rail of said intermediate portion of track and the other terminal connected with the remaining rail of said first section, and means controlled by said relay for supplying alternating current to the remaining winding of said track relay.

6. In combination, a stretch of railway 90 track divided into a first and a second track section by a short intermediate portion of track separated from both said sections by insulated joints in the track rails, a source of alternating current connected across the rails of one said section, a track relay having two windings one of which is connected across the rails of the other section, an asymmetrical unit connected across one of said insulated joints, a detector relay responsive to uni-directional current but not to alternating current and connected with said 100 source through said asymmetrical unit

joints breaks down, and means controlled by said detector relay for supplying alternating current to the remaining winding of said track relay. 10

In testimony whereof I affix my signature.

ROBERT M. GILSON.
